THOMAS HARDCastle, OF THE BRADSHAW WORKS, NEAR BOLTON,
ENGLAND.

Design No. 4,792, dated April 11, 1871.

DESIGN FOR A PRINTED FABRIC.

The Schedule referred to in these Letters Patent and making part of the same.

To all whom it may concern:

Be it known that I, THOMAS HARDCastle, of the Bradshaw Works, Bolton, in the county of Lancaster, in England, have invented a new and original Design for Printed Fabrics; and I do hereby declare that the following is a full, clear, and exact description thereof, which will enable others skilled in the art to make and use the same, reference being had to the accompanying specimen forming part of this specification.

The nature of my invention is fully represented in the accompanying photographic illustration, to which reference is made.

I claim as my invention—

The design for printed fabrics, as shown.

THOMAS HARDCastle.
